UNITED STATES PATENT OFFICE.

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

DESIGN FOR AN ELECTRIC HEATING UNIT.

Application filed November 30, 1923. Serial No. 7,917. Term of patent 14 years.

To all whom it may concern:

Be it known that I, EDWIN A. RUTENBER, a citizen of the United States, residing at the city of Milwaukee, in the county of Milwaukee and State of Wisconsin, have invented a new, original, and ornamental Design for Electric Heating Unit, of which the following is a specification, reference being had to the accompanying drawing, forming a part thereof.

The figure of the drawing is a plan view of an electric heating unit illustrating my design.

I claim:

The ornamental design for an electric heating unit as shown.

Signed at the city of Milwaukee, in the county of Milwaukee, and State of Wisconsin, this 22nd day of November, 1923.

EDWIN A. RUTENBER.
